FLUID DISPLACING PUMP

Edward F. McCarthy, Chicago, Ill., assignor of
one-half to Charles H. McCarty, Chicago, Ill.

Application May 26, 1934, Serial No. 727,601

3 Claims. (Cl. 230—75)

This invention relates to improvements in fluid displacing pump and more particularly, but not exclusively, high vacuum pumps especially useful in maintaining high vacuums in condenser systems and the like.

One general object of the invention is to provide a pump of the character indicated which is extremely efficient in operation; effects an exceptionally high vacuum; and is of simple and relatively inexpensive construction.

More specifically, an object of the invention is to provide a centrifugally operating pump of the character indicated wherein the impeller operates within the body of a circulating liquid and the vanes thereof are passed successively over liquid and fluid outlet ports of a stationary valve or post member, the construction being further characterized by the employment of stationary baffles and strippers around the impeller so located and arranged as to insure maintenance of the displacement or vacuum areas on the inner sides of the impeller vanes and to separate the gaseous fluids near the peripheral portions of the impeller from the slugs of liquid carried thereby when passing from a position over the liquid outlet port to the fluid outlet port.

Other objects of the invention will more clearly appear from the description and claims hereinafter following.

30 In the drawing forming a part of this specification, Figure 1 is a vertical diametrical sectional view of a pump having incorporated therein one embodiment of the invention. Figures 2, 3 and 4 are vertical, sectional views corresponding to the section lines 2—2, 3—3 and 4—4 respectively of Figure 1, Figures 2 and 4 being upon an enlarged scale. And Figure 5 is a detailed sectional view corresponding to the section line 5—5 of Figure 2.

In said drawing, a casing or vessel of suitable form and capacity is provided, the same preferably being comprised of a main casting having an outer vertical end wall 10, bottom wall 11, U-shaped side walls 12—12, intermediate partition 13 and opposite end wall 14 having an opening therein for the reception of a liquid-tight removable closure wall 15. The capacity of the casing is preferably augmented by means of a box-like superstructure 16 removably secured thereto but with a sealed joint, said box-like member 16 having a sloping partition 17 therein and provided with a fluid outlet pipe 18 and liquid overflow pipe 19. From the preceding description, it will be seen that the casing provides two

which circulates in the direction indicated by the arrows shown in Figure 1.

Preferably formed integral with the end wall 10 is an annular hollow ring-like fluid admission chamber 82 to which the fluid to be displaced, such as air, is admitted as by the inlet pipe 81. On the opposite or inner side of the end wall 10 is preferably integrally formed upper and lower approximately semi-circular fluid passages 22—22, the interiors 23 of which are in communication with the fluid chamber 20. As will be obvious, the stationary passages 22 are disposed within the liquid chamber 20 and the circulating liquid is admitted between the members 22 through the diametrically disposed ports 24, 15 as indicated by the arrows in Figure 3.

The dividing partition 13 of the casing is centrally apertured and is adapted to have removably attached thereto what may be termed a ported stationary post or valve member designated generally by the reference character A, it being understood that a sealed joint is effected between the member A and the partition 13 when the same are bolted together as by the bolts 25 extended through the peripheral flange of 25 the member A. Said member A comprises two central, approximately semi-circular sectioned hollow posts 26—26, each of the same having an inner flat, transversely extending section 27, an outer circular section 28 and end wall 89. 30 The two sections 26, as best shown in Figure 2, are separated and provide a diametrical passage 29 with end outlet ports 30—30, the inlet for the passage 29 being axially aligned with the liquid passage provided between the two fluid conducting sections 23—23 shown in Figure 3. The circular outer section 28 of each post member is provided with a fluid outlet port 31, the same being disposed at 90° with reference to the liquid outlet ports 30 in the embodiment shown in the drawing. As will be apparent, the fluid, such as air, is admitted to the post sections 26 through the righthand ends of the latter, as viewed in Figure 1 and which are in alignment with the fluid passages 23 previously referred to.

In addition to the post or valve sections 26, the member A has preferably formed integrally therewith arcuate and concentric partitions or baffles 32—32 and strippers or diffusers 33—33. The baffles 32 as shown in Figure 2, are disposed opposite the fluid outlet ports 31 and are of considerable extent circumferentially so as to extend considerably to each side of the corresponding port 31, but not over the liquid outlet ports 30. The strippers 33, preferably of spiral 55

or involute form, are so disposed that the advance or separating edges 34 thereof are opposite the liquid outlet ports 30. As best shown in Figure 5, the strippers have associated therewith at each end thereof not only the attaching flange 35 of the member A but also opposite flanges 36 so as to provide defined passages for the discharge of the slugs of liquid under centrifugal force through the discharge openings

10 37-37.

Cooperable with the stationary post or valve member A is the impeller designated generally by the reference character B, the latter having a hub 38 keyed to the operating shaft 39, a main web 40 and a pair of integral annular webs 41 and 42 encircling the post members 26-26. Extending between and integrally formed with the impeller web sections 41 and 42 is a series of involute vanes 43-43, the inner edges of which are adapted to rotate over and in close proximity to the post members 26-26 and the outer edges of which pass in close proximity to the stationary baffles 32 and advance separating edges of the strippers 33, as will be apparent from Figure 2.

The shaft 39 is mounted in suitable outboard bearings 44-44 on opposite sides of the casing and suitable packing and glands, as indicated at 45-45, are provided where the shaft extends 30 through the end wall 10 and removable closure wall 15.

Assuming a proper quantity of liquid within the casing and the shaft rotated under relatively high speed as by a suitable motor or other prime mover, the operation of the pump is as follows. As the vanes of the impeller successively pass over the liquid outlet ports 30 of the post member, slugs of the liquid are obviously picked up thereby and moved out under centrifugal force, as will be apparent. There is thus created on the under or inner sides of the vanes, an area of decreased or lowered pressure creating a vacuum so that, as the vanes thereafter successively pass over the fluid outlet ports 31, the air or other fluid passes out through said ports into the area of reduced pressure beneath the vanes. As the vanes pass under the strippers 33, portions of the slugs of liquid will be thrown out or discharged through the discharge ports 37 while the remaining portions of the liquid slugs as the vanes pass beneath the stationary baffles 32, will be retained between the baffles and the outer end portions of the vanes, thus providing a seal as the vanes pass beneath the baffles 32 and over the fluid discharge ports 31. In this manner, by thus maintaining the seal, maintenance of the areas of reduced pressure beneath the impellers is insured as the vanes pass over the fluid outlet ports 31.

60 By employing the strippers or separators 33, the fluid as delivered from one fluid outlet port to the under sides of the vanes, is prevented from being carried around to a position opposite the next fluid outlet port since the fluid being lighter than the liquid, tends to seek the periphery of the impeller as the vanes of the latter pass out from under the stationary baffles 32 and hence, in the movement from the rear edge of a baffle 32 to the next adjacent stripper 33, the fluid, such as air, will be separated or stripped by the stripper from the corresponding slug of liquid then being picked up by the vane as it passes over the corresponding adjacent liquid outlet port 30 of the post member. This further insures the maintenance of the vacuum or area of reduced pres-

sure beneath the vanes as the latter pass beneath the stationary baffles 32.

Obviously, as the liquid and fluid are discharged into the chamber 21, both rise therein and the gaseous fluid then separates from the liquid and passes out through the outlet pipe 12 and the liquid then circulates over the inclined partition 17 and back through the casing through the chamber 20 as before. The partition or baffle 17 is preferably disposed in the manner shown in Figure 1 so as to provide a larger area on the lefthand side thereof for easier freeing of the air or fluid from the liquid.

Although the preferred form of the invention has herein been shown and described, nevertheless the same is by way of illustration only and not by way of limitation since it is obvious that various changes and modifications may be made as, for instance, in the number and character of the vanes on the impeller, the number of ports in the post or port member as well as variations in the location and extent of the baffles and strippers 32 and 33. All changes and modifications are contemplated that come within the scope of the claims appended hereto.

What is claimed is:

1. In a pump of the character described, the combination with a casing to contain a circulating liquid and provided with a fluid outlet; of a stationary member within the casing and ported for the inlet and outlet of a liquid respectively from and return to the casing, said member being also independently ported for the inlet of a fluid from the exterior of the casing and for the outlet of the fluid into the casing; a vaned impeller rotatable about said stationary member in such manner that the inner ends of the vanes successively pass over the liquid and fluid outlet ports of said member; a stationary partition exteriorly concentric with the impeller and disposed opposite the fluid port outlet of the stationary member to thereby maintain an area of reduced pressure beneath a vane while passing over the fluid outlet; a stationary fluid stripper adjacent the periphery of the impeller and having its advance edge opposite the liquid outlet port of the stationary member, said partition and stripper being spaced from each other to thereby permit the discharge of liquid and fluid from the impeller into the casing; and means for conducting the fluid to be displaced from outside of the casing to said stationary member.

2. In a pump of the character described, the combination with a chambered casing adapted to contain a circulating liquid and provided with a fluid outlet; of a stationary valve member disposed within one of the chambers and having circumferentially spaced independent liquid and fluid outlet ports; means for admitting the circulating liquid from the other of said chambers to said valve member and thence to said liquid outlet port; means for admitting fluid from a source exterior of the casing to said valve member and to said fluid valve outlet port; an impeller having involute vanes rotatable around said valve member and successively past said liquid and fluid outlet ports; and stationary, circumferentially spaced and alternated baffle and stripping means around the periphery of the impeller, the spaces between said baffle and stripping means communicating with that chamber in which the stationary valve member is disposed whereby the liquid and fluid are discharged into said chamber from the impeller.

3. In a pump of the character described, the

combination with a casing having a partition therein dividing the same into two chambers for the circulation of a liquid therethrough and provided with a fluid discharge outlet; of a stationary valve member disposed within one of said chambers, said valve member having alternated circumferentially separated and independent liquid and fluid outlet ports, said valve member having an inlet for the circulating liquid from the other of said chambers and an independent fluid inlet from the exterior of the casing; stationary circumferentially spaced and alternated

strippers and baffles arranged around said valve member, the strippers extending over the liquid outlet ports and the baffles over the fluid outlet ports the spaces between the strippers and baffles communicating with that chamber in which the stationary valve member is disposed whereby the liquid and fluid are discharged into said chamber from the impeller; and a vaned impeller cooperable with and rotatable between the valve member and said strippers and baffles.
